Quincy, Mass., a corporation of Massachusetts

Application January 28, 1933, Serial No. 654,028

4 Claims. (Cl. 229—14)

This invention relates to a package and to a method of making a package.

One object of the invention is to provide a novel and improved construction of package adapted to be closed and sealed in a novel manner to effectively seal the contents of the package.

A further object of the invention is to provide a novel and improved lined package in which provision is made for closing and sealing the mouth of the liner in a novel and improved manner.

Another object of the invention is to provide a novel method of making a closed and sealed package by which the mouth of the package may be closed and sealed in a novel, efficient and practical manner.

With these objects in view, and such others as may hereinafter appear, the invention consists in the package and in the method of making the package hereinafter described and particularly defined in the claims at the end of this specification.

In the drawing illustrating the preferred embodiments of the invention, Fig. 1 is a perspective view of a lined package embodying the present invention in a condition ready to be filled and subsequently closed; Fig. 2 is a similar view of the mouth portion of a lined package illustrating another embodiment of the invention; Fig. 3 is a perspective illustrating the package shown in Fig. 2 after the mouth of the lining has been closed and sealed; Fig. 4 is a side elevation of the package in the condition shown in Fig. 3; Fig. 5 is a plan view of the package with the upstanding closed and sealed mouth of the lining folded down preparatory to closing the flaps of the package itself; Fig. 6 is a plan view illustrating the top of the package after the flaps have been closed; and Fig. 7 is a perspective of the completely filled, closed and sealed lined package.

In the packaging of various commodities, it has heretofore been proposed to package the commodity in a lined package comprising a carton provided with a paraffin bag or liner within the carton. After the lined package has been produced, it is usually filled by machine, and thereafter it has been the more recent practice to close the mouth of the liner and seal the same by melting together the paraffin coating on the contacting surfaces of the folded flaps of the mouth of the liner in the attempt to provide a tight seal for the mouth of the liner. The strength of the paraffin seal thus produced, however, is not as great as is desirable, and, accordingly, one of the aims of the present invention

is to provide a package having a similarly paraffined paper liner in which the mouth of the liner is closed and sealed in a novel manner such as to provide a superior and much stronger seal than has heretofore been possible to produce with the hot sealing methods heretofore used.

The present invention, therefore, contemplates in its broader aspects a moisture-proof package or bag which may take the form of a paper bag or a liner for a carton, and in which the moisture-proof coating does not extend to the mouth of the bag but terminates a sufficient distance therefrom to provide an uncoated portion of the paper capable of being utilized to provide a paper to paper contact adapted to be sealed by glue or other adhesive and thereby provide a moisture-proof package or bag having its mouth sealed by a superior and much stronger seal. It is preferred to close the mouth of the package or bag by folding outwardly the opposite end portions of the mouth of the package or bag to enable a continuous seal from one side of the bag to the other to be produced, and thereafter the mouth of the bag may be folded in any desired manner to form the completed package. In its preferred form the invention is embodied in a paraffin lined package, and provision is made in accordance with the present method for removing a band of paraffin around the mouth of the liner, preferably from either the inside or from both the inside and outside of the mouth thereof, to thereby provide an exposed uncoated sealing portion, enabling the same to be brought into contact and glued or otherwise adhesively affixed together. Thereafter the sealed mouth portion of the liner may be folded down within the outer package and the flaps of the latter may be closed and sealed in any usual or preferred manner.

Referring now to the drawing, 10 represents a package or carton which may be made in any usual or preferred manner and is herein shown as provided with bottom flaps 12 and top flaps 14. The bottom flaps 12 may be closed and sealed in any suitable bottom sealing machine or in any other suitable manner. The carton or package 10 is in accordance with the present invention provided with a moisture-proof liner or bag 16 within the same, and the mouth of which is arranged to project above the top of the opened package in the manner illustrated in Figs. 1 and 2. The mouth portion of the liner 16 is provided with an uncoated band or strip 20 extending around the mouth of the bag, preferably around the marginal portion of the mouth of the bag, as illustrated in Figs. 1 and 2. In practice the mois-

ture-proof liner may comprise a bag of paraffined paper and the sealing band may conveniently be formed by removing the paraffin coat from either the inner marginal surface of the mouth of the liner, as illustrated in Fig. 1, or from both the inner and outer surfaces, as illustrated in Fig. 2. If desired during the operation of coating the paper with paraffin, an uncoated portion may be left to form the sealing band 20 after the bag or liner is formed. In accordance with the usual practice of manufacturing paraffin coated paper bags such as heretofore have been used as liners, the side seams 18 of the bag are formed by overlapping the paraffin coated marginal edge portions of the sheet and heat sealing the same, whereby to produce a bag having its body portion entirely covered with paraffin so that most effective resistance is offered to the passage of moisture through the body of the bag.

20 The package with the liner arranged as shown in Figs. 1 and 2 is then in a condition for filling and closing, and the filling operation may be performed by hand or by any suitable filling mechanism, and after the liner has been filled, provision is made for closing the mouth portion of the liner in such a manner as to bring together the uncoated portions of the mouth of the liner, or the sealing band 20, in order to permit the mouth of the liner or bag to be adhesively affixed together by glue or by other suitable adhesive and to provide a superior and strong seal for the same. As illustrated in Figs. 3 and 4, the opposite end portions of the liner may be folded outwardly to effect the closing of the mouth of the liner, and prior to the actual closing of the same, those portions of the uncoated sealing strip which are to be brought into contact may and preferably will be provided with adhesive, so that when the folding operation is completed and the contacting faces of the sealing strip pressed together, a desirable and strong seal is provided extending entirely across the mouth of the bag or liner.

45 After the bag has thus been filled, closed and sealed, the projecting portion of the mouth of the liner may and preferably will be folded down into the position shown in Fig. 5, after which the projecting end flaps may be folded inwardly into the position shown in Fig. 6, to thereafter permit the top flaps 14 of the carton to be closed and sealed in the usual manner to provide the completely sealed package shown in Fig. 7.

50 While the preferred embodiment of the invention has been herein illustrated and described, it will be understood that the invention may be

embodied in other forms within the scope of the following claims.

Having thus described the invention, what is claimed is:—

5 1. As a new article of manufacture, a lined package comprising an outer package and a coated moisture-proof paper liner within the package, the body portion of said liner being provided with a moisture-proof coating co-extensive with the entire surface thereof with the exception of an uncoated sealing band around the inside of the mouth thereof, the ends of the mouth of the liner being folded outwardly to bring the remaining sides thereof in contact, and the contacting portions of the uncoated sealing band being adhesively secured together to form a paper to paper seal across the entire mouth of the liner.

10 2. As a new article of manufacture, a lined package comprising an outer package and a coated moisture-proof paper liner within the package, the body portion of said liner being provided with a moisture-proof coating co-extensive with the entire surface thereof with the exception of an uncoated sealing band around the inside of the mouth thereof, the ends of the mouth of the liner being folded outwardly to bring the remaining sides thereof in contact, and the contacting portions of the uncoated sealing band being adhesively secured together to form a paper to paper seal across the entire mouth of the liner, said sealed mouth of the liner being folded down into the package.

15 3. As a new article of manufacture, a lined package comprising an outer package and a paraffin coated paper liner within the package, the body portion of said liner being provided with a paraffin coating co-extensive with the entire surface thereof with the exception of an uncoated sealing band around the inside of the mouth thereof, the ends of the mouth of the liner being folded outwardly to bring the remaining sides thereof in contact, and the contacting portion of the uncoated sealing band being adhesively secured together to form a paper to paper seal across the mouth of the liner.

20 4. As a new article of manufacture, a lined package comprising an outer package and a paraffin coated paper liner within the package, the body portion of said liner being provided with a paraffin coating co-extensive with the entire surface thereof with the exception of an uncoated sealing band around the mouth thereof whereby to enable the mouth of the same to be sealed with a paper to paper contact.
